UNITED STATES PATENT OFFICE.

JAMES MADISON COCHRAN, OF GOBER, TEXAS.

WIND-MOTOR.

SPECIFICATION forming part of Letters Patent No. 703,766, dated July 1, 1902.

Application filed October 16, 1901. Serial No. 78,815. (No model.)

To all whom it may concern:

Be it known that I, JAMES MADISON COCHRAN, a citizen of the United States, and a resident of Gober, in the county of Fannin 5 and State of Texas, have invented new and useful Improvements in Wind-Motors, of which the following is a full, clear, and exact description.

The object of the invention is to provide a new and improved wind-motor which is simple and durable in construction, very effective in operation, and arranged to permit the use of large wind-wheels without danger of creating any undue torsional or other strains and 15 allow the vane to freely hold the wheel into the wind and to insure a proper transmission of the power developed.

The invention consists of novel features and parts and combinations of the same, as 20 will be fully described hereinafter and then pointed out in the claims.

A practical embodiment of the invention is represented in the accompanying drawings, forming a part of this specification, in which 25 similar characters of reference indicate corresponding parts in all the figures.

Figure 1 is a side elevation of the improvement. Fig. 2 is an enlarged sectional side elevation of the same, and Fig. 3 is an en- 30 larged side elevation of the gearing.

In wind-motors as heretofore constructed it has been found impracticable to build wind-wheels of more than twelve or sixteen feet in diameter, as the tail or vane is only capable 35 of successfully bracing a twelve-foot wheel. When large wheels are used and geared to heavy machinery, the load tends to twist the wind-wheel and tail or vane to an angular position relatively to the direction of the wind, 40 so that the force of the wind is not utilized to the fullest advantage and the wheel finally comes to a stop, as it cannot carry the load.

With my improvement, presently to be described in detail, this difficulty is completely 45 overcome, and wind-wheels of any desired diameter can be built and the power developed be properly transmitted without any danger of undue strains or twist, as the vane has only its legitimate function to perform— 50 that is, to hold the wheel to the wind.

On a suitably-constructed tower A are ar- ranged the bearings A' and A², in which is

mounted to rotate the vertically-disposed hollow hub B' of the vane B, having a horizontally-disposed strengthening-rib B² extending into the hub B' and terminating in an extension B³, forming a spindle for the hollow shaft C, carrying the wind-wheel D, of any approved construction. The hollow wind-wheel shaft C has also a bearing B⁴ attached 60 to the hub B', and on the end of the said shaft within the hub B' is secured a bevel gear-wheel E, in mesh at opposite sides with the bevel-pinions F and G, secured on the upper ends of the shafts F' and G', respectively, of 65 which the shaft F' is hollow and the other shaft G' extends concentrically through it.

The shaft F' has its upper end journaled in a bearing H, carried by the hollow hub B', and the lower end of the said shaft F' is journaled in a step H', carried by the tower A. (See Fig. 1.) The shaft G' has a number of bearings I in the hollow shaft F', and the lower end of the said shaft G' is set in a step I', carried on the base of the tower A. The 75 lower ends of the shafts F' and G' carry gear-wheels F² G², in mesh with the opposite sides of the bevel-pinion J', secured on the transmission-shaft J, connected in the usual manner with the machinery to be driven. 80

Now it will be seen by the arrangement described that the rotary motion of the wind-wheel D and its shaft C is transmitted by the bevel gear-wheel E to the two pinions F and G to rotate the latter in opposite directions. 85 This motion of the bevel gear-wheels F and G is transmitted to their shafts F' and G' and to the bevel gear-wheels F² and G², and as the latter are in mesh at opposite sides with the pinion J' it is evident that this pinion J' 90 and the shaft J are rotated in one direction and with the approximately full power developed in the wheel D.

By having the gear-wheel E meshing with the pinions F and G in the manner described 95 it is evident that all torsional strain of the shaft C is counterbalanced, and consequently the vane B is completely free of such strain and can properly perform its legitimate function—that is, hold the wheel to the wind. 100

Having thus described my invention, I claim as new and desire to secure by Letters Patent—

1. The combination of a vane provided with

a shaft-bearing, a spindle carried by the vane and disposed in a concentric relation to said bearing and extending forwardly beyond the latter, a hollow wheel-shaft sleeved on said 5 spindle and journaled in said bearing, a wheel, and a driven shaft geared to said wheel-shaft.

2. The combination of a vane provided with a vertical hollow bearing and with a bar which extends across the hollow bearing and terminates in a spindle, a hollow wheel-shaft sleeved on said spindle, and driven shafts geared to the wheel-shaft, one of the driven 10 shafts being journaled in said bar.

3. A wind-motor having a vane provided with a vertical hub mounted to turn, a brace 15 for the vane-body, and an extension on the brace for forming a bearing for the wind-wheel shaft, as set forth.

In testimony whereof I have signed my name to this specification in the presence of 20 two subscribing witnesses.

JAMES MADISON COCHRAN.
